SADIRON SHELL AND REST
CONSTRUCTIONRussell I. Huffman, Strasburg, Ohio, assignor to
Dover Manufacturing Company, Dover, Ohio, a
corporation of Ohio

Application January 14, 1935, Serial No. 1,661

5 Claims. (Cl. 68—26)

An object of my invention is to provide a sadiron shell and rest construction in which the shell and rest portions are inexpensively and integral-
ly formed of a single sheet of metal.

5 A further object is to provide an article of man-
ufacture comprising a single sheet of metal
formed in a press or the like to provide a shell
portion and a rest portion, the rest portion be-
ing a continuation of the shell portion, thereby
10 eliminating the operations of separately forming
a rest portion and attaching such rest portion to
the shell portion.

Still a further object is to provide a shell and
rest construction so formed that the rest portion
15 is an integral part of the shell portion and
so connected with it that it is rigid relative there-
to, even though the material for making the de-
vice may be of quite thin sheet metal.

Still a further object is to provide a rest portion
20 integrally formed with a sadiron shell and
extending downwardly and rearwardly there-
from, the rest portion being provided with side
flanges, thereby making it channel shaped in
cross section and the side flanges being continua-
25 tions of the sides of the shell portion whereby the
rest portion is quite rigid relative to the shell portion
and reinforced against bending relative thereto,
thus resisting the ordinary strains im-
posed on the rest portion of a sadiron when sup-
30 porting the sadiron in non-operating position.

Still a further object is to provide a down
turned flange on the rear margin of the rest portion
35 to prevent any undue twisting of this portion
and provide a rounded edge to rest on the
ironing board or other surface on which the
iron is supported when not in use.

With these and other objects in view my in-
vention consists in the construction, arrange-
40 ment and combination of the various parts of my
device, whereby the objects contemplated are at-
tained, as hereinafter more fully set forth, point-
ed out in my claims and illustrated in the accom-
panying drawing, in which:

45 Figure 1 is a perspective view of a sadiron shell
and rest construction embodying my invention.

Figure 2 is a bottom plan view of the same.

Figure 3 is a longitudinal sectional view on the
line 3—3 of Figure 2.

50 Figure 4 is a side elevation showing the shell
and rest construction associated with the sole
plate of a sadiron.

55 Figures 5 and 6 are sectional views on the lines
5—5 and 6—6 respectively of Figure 3 showing
the cross sectional shape of the shell and rest
portions of the device; and

Figure 7 is a side elevation of a sadiron with
my shell and rest construction associated there-
with and showing the iron in the position in
which it is placed when not in use, which posi-
tion brings the rest portion of my invention into
play.

On the accompanying drawing I have used the
reference character S to indicate a shell portion of
a shell and rest embodying my invention and
R a rest portion. The shell portion S is semi-oval
10 or concavo-convex shaped in lateral cross sec-
tion, its parts being definable as a top wall 10,
and side walls 12.

The shell portion S is adapted for its concave
side to rest against a sole plate 14, as shown in
15 Figure 4, with the side walls 12 contacting with
a shoulder 16 on the sole plate in the ordinary
manner. The shell portion, of course, conceals
the mechanism of the iron, usually consisting
of a heating element and a weight member (not
20 illustrated). In Figure 4, I have shown only the
sole plate 14 associated with my invention while
in Figure 7 I also show a handle support 18, a
handle 20, a connector prong enclosing member
22, and a rest foot 24, the parts 14 to 24 forming
25 no part of my invention.

At the heel of the shell portion S, there are rear
wall sections or flanges 26. These serve as con-
necting flanges in a manner which will herein-
after be described.

30 The rest portion R comprises a top wall 28
forming an integral extension of the top wall 10
of the shell portion S. The wall 28 slopes down-
wardly and rearwardly from the wall 10 and
terminates in a down turned flange 30. The rest
35 portion R further includes side flanges 32 which
are also down turned, thus making the lateral
cross sectional shape of the rest member a chan-
nel as shown in Figure 6.

The ends of the rear flange 30 are integral ex-
40 tensions of the rear ends of the side flanges 32,
while the flanges 26 at the heel of the shell portion
are transition flanges between the sides 12 of the
shell portion and the forward ends of the flanges
32.

45 This particular construction just described,
wherein the sides 12 and the flanges 26, 32, and
30 are integral extensions of each other, I have
found to be a very desirable way of shaping the
shell and rest portions from one sheet of material,
50 it producing rigidity between the various elements
of the device even with the use of comparatively
thin metal.

55 Preferably the rest portion R is restricted as in-
dicated at 34 and the rear end, defined by the

bends 36 between the flanges 30 and 32, is less in width than the width of the shell portion S. Also the flange 30 is preferably concave with respect to the rear extremity of the device so that 5 a two-point support is provided at the bends 36 which in conjunction with the rest foot 24 makes a three-point support for the sadiron in the position of Figure 7 while it is not in use or in non-ironing position.

10 The flange 30 eliminates any sheet metal edge contacting with the ironing board surface 38 in Figure 7, while the flanges 32 and their particular connection with the shell S provide a rest portion R which in itself is rigid and is also rigid with respect to the shell. The shell, of course, is tightly assembled relative to the sole plate 14 and other parts of the sadiron so that the rest member R is rigid with respect to the sadiron and thereby supports the iron in the position of Figure 7 without 15 any tendency to wobble, whereas with the rest member formed separately and attached to the shell or some other part of the iron when the parts become loosened or if they are not properly reinforced and secured, wobbling will occur. It will 20 be obvious that I have provided a rigid extension on the shell member which is very effective as a rest without having to go to the expense of making a separate member and thereafter securing it 25 in position.

30 Some changes may be made in the construction and arrangement of the parts of my device without departing from the real spirit and purpose of my invention, and it is my intention to cover by 35 my claims any modified forms of structure or use of mechanical equivalents which may be reasonably included within their scope.

I claim as my invention:

1. A sadiron shell and rest member formed of a single sheet of metal, said rest member being an 40 integral continuation of said shell and extending both rearwardly and downwardly from the top thereof and terminating in a relatively vertically narrow end for providing a supporting edge substantially below the top plane of the shell when 45 the rest is in position where it can function, said rest having a downturned flange on three of its sides.
2. A sadiron shell and rest member formed of a single sheet of metal, said rest member being an 50 integral continuation of said shell and extending both rearwardly and downwardly from the top

thereof and terminating in a relatively vertically narrow end for providing a supporting edge substantially below the top plane of the shell when the rest is in position where it can function, said rest having a downturned flange on the sides continuing from the sides of the shell. 5

3. In combination with a sadiron sole plate, a unitary shell and rest member pressed from sheet metal to provide a shell portion above said sole plate and a rest portion rearwardly thereof, said 10 rest portion continuing downwardly from the top of said shell and terminating closely adjacent the extended plane of the sole plate to provide a supporting edge closely adjacent said plane when said shell and rest member are in substantially tilted 15 non-operative position, said rest portion having a downturned flange on the sides continuing from the sides of the shell.

4. In combination in a sadiron, a sole plate, a single piece shell and rest member pressed from 20 sheet metal to provide a shell portion above said sole plate and a rest portion rearwardly thereof, said rest portion extending rearwardly and downwardly and terminating in a plane substantially below the horizontal plane in which the top of the 25 shell lies to provide a relatively narrow supporting edge when said shell and rest member are in substantially tilted non-operative position, a second supporting element cooperating with the narrow supporting edge to prevent tipping of the 30 iron, said rest portion including downturned flanges between the shell and the supporting edge, said supporting edge and second supporting element being both spaced substantially from the 35 vertical plane through the center of gravity of the sadiron to retain the sadiron in tilted non-operative position against accidental tipping.

5. A sadiron shell and rest member formed of a single sheet of metal, said rest member being an integral continuation of said shell and extending 40 both rearwardly and downwardly from the top thereof and terminating in a relatively vertically narrow end for providing a supporting edge substantially below the top plane of the shell when the rest is in position where it can function, said 45 rest being horizontally narrower than the shell at its junction therewith defining thereby shoulders between the shell and the rest, said rest having downturned flanges along its sides continuing along said shoulders and from said shell. 50

RUSSELL I. HUFFMAN.
